UNITED STATES PATENT OFFICE.

CHARLES M. HEETER, OF BUTLER, PENNSYLVANIA.

OIL SAVER.

Application filed September 26, 1918. Serial No. 255,766.

To all whom it may concern:

Be it known that I, CHARLES M. HEETER, a citizen of the United States, residing at Butler, in the county of Butler and State of Pennsylvania, have invented a new and useful Improvement in Oil Savers, of which the following is a full, clear, and exact description, reference being had to the accompanying drawings, forming part of this specification, in which—

Figure 1 is a side elevation of one form of my improved saver in connection with a supporting device therefor.

Figure 2 is a plan view of Figure 1.

Figure 3 is a sectional view on the line III—III of Figure 2.

Figure 4 is a sectional view on the line IV—IV of Figure 3 with the tubing omitted, and

Figure 5 is a sectional view on the line V—V of Figure 4 with the parts in their open positions.

This invention relate to an improvement in oil savers and supports therefor, and is designed to provide an inexpensive and efficient saver, which can readily be applied to the tubing when drawing old tubing from a well, as well as an inexpensive and efficient support for the saver which is arranged to readily swing the saver into position with relation to the tubing.

Another object of my invention is to provide an oil saver which is arranged to apply a greater amount of friction to that portion 35 of the tubing extending from the saver to the well than to that portion of the tubing extending from the saver to the pulling device, so that when the upper portion is rotated to disconnect the same from the portion within the well, said portion that is 40 rotated will readily slip within the saver while the other portion will be fixedly held against rotation and prevented from slipping out of the oil saver.

The precise nature of my invention will be best understood by reference to the accompanying drawings which will now be described, it being premised however, that various changes may be made in the details 50 of construction and the general arrangement of the parts without departing from the spirit and scope of my invention as defined in the appended claims.

In the drawings the reference character 2 55 designates the oil saver which is supported by means of the flexible device 3 from the

end of the jib crane 4. This jib is rotatably supported on a standard 5. 6 designates a portion of the tubing extending from the saver into the well casing, and 7 designates that portion of the tubing extending from the saver to the tubing pulling device.

The saver 2 comprises two half sections 8, which are hinged to each other by means of lugs having a hinge pin extending therethrough. The upper end of the hinge pin 9 is provided with an eye 10 to which the flexible connection 3 is connected. Each of the sections 8 is provided with a recess 11 at the top thereof, as well as a recess 12 in the lower end thereof. Seated within the recesses 11 and 12 of each section are similar semi-cylindrical packing rings or members 13 and 14, the width of the packing rings 13 being very much less than the width of 75 the packing rings 14 in the direction of the axis of the saver. One of the sections 8 of the casing is provided with longitudinal recesses 15, which extend from the recess 11 to the recess 12, and seated within these recesses 15 are flexible packing members 16. One of the sections 8 of the casing is provided with an outlet 17, between the packing members 13 and 14, to which is connected a flexible hose 18 for conveying the 85 oil to any suitable source. Pivottally connected to one of the sections 8 of the casing, is a locking lever 19 having a recess 20 therein for engaging a cam projection 21 on the other section 8 of the casing for clamping 90 the casing about the tubing to be drawn.

The operation of the device is as follows:

The tubing is raised by means of the usual elevator to bring a coupling member, such as 22, to the position shown in Figures 1 and 3, and supported on the well casing 25 by means of another elevator 26. The casing 2 is then securely clamped about the coupling member 22 and the portion 7 of the tubing. When the casing 2 is clamped 100 in position, the packing member 13 will form a tight joint about the portion 7 of the tubing, while the packing members 14 will form a tight joint about the coupling member 22, and at the same time the packing members 16 will prevent any leakage 105 between the packing members 13 and 14. The portion 7 can then be freely rotated to disconnect it from the coupling member 22 as the frictional engagement between the 110 portion 7 and the packing 13 is very much less than the frictional engagement between

the packing 14 and the coupling 22. This difference in frictional engagement is caused by the greater contact area of the packing members 14, as well as the position of the 5 clamping lever which is very much closer to the packing 14 than to the packing 13. After the portion 7 has been disconnected from the coupling 22, it is slightly elevated to the position shown in Figure 3 to permit 10 the oil to flow therefrom through the tubing 18. After the portion 7 has been drained the oil saver is opened and swung to the position shown in dotted lines in Figure 2, the 15 pulling device is then connected to the elevator 26, below the coupling 22. The tubing is then raised to bring the next coupling member 22 to be disconnected to its proper position with relation to the saver, which is again clamped about the tubing as before 20 described.

The advantages of my invention result from the provision of an oil saver having separable sections, so arranged that a greater amount of friction will be created between 25 the packing members which engage the lower portion of the tubing, than that between the upper packing members and the tubing whereby the portion of the tubing, below the oil saver is rigidly held against 30 rotation while the upper portion can be readily rotated to uncouple the tubing and also to permit the upper portion to be moved relatively to the lower portion to drain the oil therefrom. Also from the provision of 35 a saver whose lower packing members are of greater area than the upper packing members, whereby the lower portion of the well casing or tubing will be held against rotation when the upper portion is rotated to 40 uncouple the same.

Still a further advantage of my invention

results from an improved means for supporting the saver at a predetermined point above the mounting level, which means is so arranged that the saver can readily be swung 45 into operative position with relation to the well tubing to be drawn.

I claim:

1. An oil saver having a plurality of separable sections, packing members in each end 50 of said sections adapted to engage casing portions of different diameters, the width of the contacting surfaces of the packing members at one end of the saver being materially greater than the width of the contacting surfaces of the packing members at the other end of the saver, said packing members of greater width being effective 55 for preventing rotation of the portion of the casing engaged thereby during rotation of 60 the portion of the casing engaged by the other packing members, and means for locking said sections about the casing to be drawn.

2. As an article of manufacture, a sectional oil saver having packing members in the opposite ends thereof, said packing members in one end of the saver having a width at least twice that of the packing members in the other end of the saver, 70 whereby a greater clamping action is exerted adjacent one end of the saver than the other, the clamping action exerted by the members of greater width being effective 75 for preventing rotation of the portion of the casing engaged thereby during rotation of the portion of the casing engaged by the members of lesser width, substantially as described.

In testimony whereof, I have hereunto set 80 my hand.

CHARLES M. HEETER.
